UNITED STATES PATENT OFFICE.

WALLACE MINARD, OF OIL CITY, PENNSYLVANIA.

DRILL-ROD COUPLING.

No. 904,810.

Specification of Letters Patent.

Patented Nov. 17, 1908.

Application filed February 28, 1908. Serial No. 418,324.

To all whom it may concern:

Be it known that I, WALLACE MINARD, a citizen of the United States, residing at Oil City, in the county of Venango and State of Pennsylvania, have invented a new and useful Drill-Rod Coupling, of which the following is a specification.

This invention relates to rod couplings and more particularly to improved means for effecting the union of the adjacent ends of sucker rods.

The object of the invention is to provide a coupling capable of being quickly placed in position on the adjacent ends of the rods to be united, and by means of which said rods may be effectually locked against accidental separation during the drilling operation.

A further object is to provide a coupling including a split sleeve or clamping member having a socket formed therein for the reception of the terminal heads of the rod sections to be united, said heads being held within the clamping member by means of a tapering sleeve engaging the exterior walls of said clamping member.

A still further object of the invention is generally to improve this class of devices so as to increase their utility, durability and efficiency.

Further objects and advantages will appear in the following description, it being understood that various changes in form, proportions and minor details of construction may be resorted to within the scope of the appended claims.

In the accompanying drawings forming a part of this specification: Figure 1 is a side elevation of a rod coupling constructed in accordance with my invention a portion of the sleeve and collar being broken away. Fig. 2 is a similar view partly in section. Fig. 3 is a perspective view showing the several parts disconnected. Fig. 4 is a perspective view of one of the sections comprising the split sleeve.

Similar numerals of reference indicate corresponding parts in all of the figures of the drawings.

The improved coupling forming the subject matter of the present invention is especially designed for uniting the adjacent ends of sucker rods and in Fig. 1 of the drawings is shown in position on a sucker rod in which 5 designates one section and 6 the mating section.

The rod sections 5 and 6 are provided with

terminal heads 7 preferably cylindrical in shape, as shown, and adapted to register with each other when the sections are united, there being a collar 8 formed on each rod section and spaced from the adjacent head, as shown.

Disposed at the juncture of the rod sections 5 and 6 is a clamping member preferably formed in two sections 9 and 10 each having one end thereof extended laterally to form an annular flange 11 adapted to bear against the adjacent collar 8.

The members 9 and 10 are formed with chambers adapted to register with each other to form a pocket 12 for the reception of the heads 7, there being shoulders 13 constituting the end walls of the pocket and adapted to bear against the outer faces of the heads 7 when the members 9 and 10 are assembled thereby to lock the heads in contact with each other.

The exterior walls of the sections 9 and 10 constituting the split clamping member are inclined or tapered for engagement with a correspondingly tapered clamping sleeve or collar 14, which latter, bears against the flange 11 and is locked in engagement therewith by a split key 15.

The key 15 is preferably in the form of a ring and is interposed between the reduced end of the sleeve 14 and the fixed collar 8 on the section 5 with its inner face bearing against the adjacent end of the sections 9 and 10 constituting the clamping member. Suitable grooves or recesses 16 are preferably formed in the sections 9 and 10 on each side of the socket 12 for the reception of oil or other lubricant.

By making the heads 7 cylindrical in shape, said heads are free to rotate within the socket 12 so as to permit movement of one rod section relatively to the other without danger of accidental separation of said sections.

In using the device the rod sections are brought together with the heads 7 in contact with each other, after which the members 9 and 10 are placed in position at the juncture of said rod sections and the tapering sleeve or collar 14 forced downwardly in engagement with the exterior walls of the sections 9 and 10, the locking ring or key 15 being subsequently interposed between the reduced end of the collar 14 and the adjacent fixed collar 8 and the walls of said collar at the split portion 16' thereof pressed inwardly with a chisel or other suitable tool.

The flanges 11 of the sections 9 and 10 are preferably provided with segmental recesses or depressions 17, the walls of which incline downwardly towards the reduced end of the 5 clamping collar 14 so that after the ring or key 15 is removed the point of a chisel may be inserted in the depressions 17 to assist in forcing the collar 14 off the split clamping member when it is desired to detach the rod 10 sections 5 and 6 for any purpose.

From the foregoing description it will be seen that there is provided an extremely simple, inexpensive and efficient device admirably adapted for the attainment of the 15 ends in view.

Having thus described the invention what is claimed is:

1. The combination with mating rod sections having terminal heads, of a split member 20 embracing the rod sections and having a socket for the reception of the heads, a clamping sleeve engaging the exterior walls of the split member, and a flange projecting laterally from one end of the split member 25 and having a depression formed therein and extending in the direction of the clamping sleeve.

2. The combination with mating rod sections having terminal heads and fixed collars, of a split member embracing the rod 30 sections and having a socket formed therein for the reception of the heads, a clamping sleeve engaging the exterior walls of the split member, and a locking key interposed 35 between the split member and adjacent fixed collar and bearing against the clamping collar.

3. The combination with mating rod sections each having a terminal head and a 40 fixed collar, of a clamping member including separable sections each provided with a laterally extending flange, said sections being provided with interior chambers adapted to register with each other to form a socket for 45 the reception of the heads of the rods to be united, a sleeve engaging the exterior walls of the separable sections, and a locking key interposed between the clamping sleeve and fixed collar and bearing against the adjacent 50 ends of the separable sections.

4. The combination with mating rod sections each having a terminal head and a fixed collar, of a split member including separable sections each having a laterally extending flange adapted to bear against the fixed collar of one of the rod sections, a clamping sleeve engaging the exterior walls of the separable clamping sections, and a 55 split ring interposed between the clamping sleeve and the adjacent fixed collar and bear-

ing against the adjacent ends of the separable sections.

5. The combination with mating rod sections each provided with a terminal head and a fixed collar, a split clamping member 65 including separable sections having tapering exterior walls and each provided with a flange adapted to bear against the adjacent fixed collar, a correspondingly tapering clamping sleeve engaging the exterior walls 70 of the separable sections, and a locking key interposed between the clamping sleeve and the adjacent fixed collar and bearing against the reduced ends of the separable sections.

6. The combination with mating rod sections each having a terminal head and a fixed collar, of a split clamping member having tapering exterior walls and provided with a socket for the reception of the heads of the rods, said split clamping member being provided with a laterally extending flange adapted to bear against the fixed collar on the adjacent rod section, a correspondingly tapering clamping sleeve engaging the exterior walls of the split member, and a split 85 locking ring interposed between the clamping sleeve and the fixed collar on the adjacent rod section and bearing against the reduced end of the split clamping member, there being depressions formed in the flanges 90 of the split member and having their walls inclined in the direction of and extending to the enlarged end of the clamping sleeve.

7. The combination with mating rod sections having terminal heads and each provided with a fixed collar, of a split clamping member including separable sections each having their interior walls provided with a chamber adapted to register with the chamber of an adjacent section for the reception 10 of the terminal heads of the rod sections, a flange extending laterally from each section of the split clamping member and having a depression formed therein the walls of which are inclined, a tapering clamping sleeve engaging the exterior walls of the separable sections, and a split ring interposed between the clamping sleeve and the fixed collar on the adjacent rod section and bearing against the reduced ends of the separable sections, 11 there being grooves disposed on opposite sides of the chambers in the separable sections and adapted to receive a lubricant.

In testimony that I claim the foregoing as my own, I have hereto affixed my signature in the presence of two witnesses.

WALLACE MINARD.
